CLAIM

The ornamental design for a shopping cart attachment, as shown and described.

DESCRIPTION

FIG. 1 is a perspective view of a shopping cart attachment showing a first embodiment of our new design;

FIG. 2 is a front elevation view thereof;

FIG. 3 is a right side view thereof, the left side view being a mirror image;

FIG. 4 is a top plan view thereof;

FIG. 5 is a bottom plan view thereof;

FIG. 6 is a rear view thereof;

FIG. 7 is a front elevation view of shopping cart attachment showing a second embodiment of our new design;

FIG. 8 is a right side view thereof, the left side view being a mirror image;

FIG. 9 is a top plan view thereof;

FIG. 10 is a bottom plan view thereof;

FIG. 11 is a rear view thereof;

FIG. 12 is a front elevation view of shopping cart attachment showing a third embodiment of our new design;

FIG. 13 is a right side view thereof, the left side view being a mirror image;

FIG. 14 is a top plan view thereof;

FIG. 15 is a bottom plan view thereof; and,

FIG. 16 is a rear view thereof.
